UNITED STATES PATENT OFFICE

WILHELM KOSFELD, OF DORTMUND, GERMANY, ASSIGNOR TO VEREINIGTE STAHLWERKE AKTIENGESELLSCHAFT, OF DUSSELDORF, GERMANY

FOLLOWER FOR LINE TEMPLATES

Application filed September 27, 1927, Serial No. 222,381, and in Germany October 5, 1926.

It is well known that the tools of grinding, or milling machines may be guided by means of bodies of revolution along a line template. In order to compensate, however, for any 5 wear or differences in the diameter of such tools, it was necessary to provide at the ends of said tools, special, complicated and expensive devices for the purpose of adjusting the tools relatively to the supporting 10 rollers. Another way of obviating this difficulty was to change the templates.

This invention provides on the contrary a means of simply and accurately setting the grinding or milling roller by making the rollers, which are arranged at the end of the roller and which travel on the line templates, conical instead of cylindrical. The largest cone surface diameter preferably corresponds in such a case to the greatest diameter of the 15 grinding roller. If the diameter of the grinding roller is reduced by grinding or wear, it is merely necessary to move the conical rollers to such an extent that a smaller surface diameter touches the template.

20 The accompanying drawings show by way of example a construction for such a stone grinding machine:

Figure 1 illustrates an end elevation of a 25 grinding machine with the new devices.

Figure 2 illustrates the left portion of the 30 grinding roller in an enlarged scale.

Figure 3 is a fragmentary side elevation 35 illustrating the detailed construction of the rotatable mounting of the roller, motor and etc.

On the table *h* of the grinding machine two 40 brackets *j* and *k* are screwed. In the bracket *k* is mounted a worm drive *l, m*. In the worm wheel *m* is a bush or sleeve which passes 45 through the upper part of the bracket *k* and in which is mounted an adjustable spindle *n* which is free to revolve and on which is mounted a template *c*. In the bracket *j* is mounted a simple spindle *o* with a locking 50 device *p* therefor. On each of the spindles *n* and *o* Morse cones *q, q'* are mounted. Said cones are provided with clamping plates or jaws *r* which may be adjusted to support 55 the work *s*.

The spindle of the grinding roller *a* carries at its ends conical rollers *b* loosely rotatable on their spindle, the diameter of which at the base corresponds to the diameter of the grinding roller, and the cone axis of 55 which coincides with the roller axis. The points of the cone are facing each other. At the base of the cone is arranged a pressure plate *d* fixed by an arm *e* and holding the cone *b* in position with the interposition of 60 a ball thrust bearing. The arm *e* is rigidly secured to a sleeve with an inner thread. This sleeve is guided in a neck bearing *f* which is secured to the bearing frame of the 65 grinding roller. By means of the screw spindle *g* with hand wheel, the arm *e* is moved in the direction of the axis of the grinding roller. As the weight of the grinding roller is transmitted to the conical roller, the roller *b* slides when the arm *e* is screwed out of 70 the neck bearing, corresponding to this movement from the preferably rounded off template, so that no further devices are required for keeping the roller *b* in the desired position relatively to the arm *e* corresponding to 75 the diameter of the grinding roller at the time:

It is preferable to provide the conical rollers at the base with a short cylindrical projection corresponding to the largest diameter 80 of the grinding roller, in order to operate with the cone surfaces only when the grinding roller is worn.

The whole grinding portion of the apparatus is adjustable about axes arranged at 85 right angles to each other. The vertical columns *t* of the super-structure of the apparatus rigidly support an axle *x* the axis of which is parallel to the axis of the spindles *n* and *o*. A bearing member *z* encloses 90 said axle *x* and is free to rotate thereon. A second axle *y* is also enclosed in bearing member *z* and free to turn therein. The axis of axle *y* is at right angles to the axis of axle *x* 95 and parallel to the longitudinal axis of the machine. A bracket *w* rotates freely upon axle *y* and supports the motor *u* which supplies the motor power for the grinding tool. The grinding tool is rotatably mounted be- 100

tween arms v , v' which are integral with the bracket z .

What I claim and desire to secure by Letters Patent of the United States is:

- 5 1. A machine for grinding articles comprising a bed for the article to be shaped, a grinding roller above the bed, said bed being relatively movable in the direction of the longitudinal axis of the machine, means for supporting the grinding roller, said means including means permitting rising and falling movement of the roller and means permitting tilting of the roller, templates mounted above the bed, conical rollers mov-
10 able with said roller and cooperating with said templates to cause any predetermined rising and falling and tilting movement thereof, means for axially adjusting said conical rollers, and means for rotating the grind-
15 ing roller.
2. A grinding machine according to claim 1 in which said means for axially adjusting said conical rollers comprises an arm controlling the axial movement of said conical roll-
20 ers, said arm being slidable within a neck bearing and actuated by a screw spindle and a hand wheel.
